ELECTRIC CONNECTING PLUG

Charles H. Kohne, Pittsburgh, Pa.

Application January 17, 1939, Serial No. 251,349

1 Claim. (Cl. 173—361)

This invention relates to an electric connecting plug, of the prong type commonly employed in connection with an extension cord for joining electrically operated appliances, such as lamps, sweepers, refrigerators, washers, irons, toasters, and the like, with the source of electrical supply.

Difficulty has been encountered with the conventional cord and plug set due to the severance and loosening of the conductors from screw and plug terminals, either from repeated handling or from material deterioration, with resultant hazardous short circuits.

Important objects and advantages of the present invention are to provide an electric connecting plug of the character described, which will greatly reduce accidental disconnection of conductors and which will permit anyone to make simple interchangeable replacements when required, which is simple in its construction and arrangement, durable and efficient in its use, attractive in appearance, and economical in its manufacture, attachment, and maintenance.

With the foregoing and other objects in view which will appear as the description proceeds, the invention resides in the novel construction, combination and arrangement of parts herein specifically described and illustrated in the accompanying drawing, but it is to be understood that changes in the form, proportions, and details of construction may be resorted to that come within the scope of the claim hereunto appended.

In the drawing wherein like numerals of reference designate corresponding parts throughout the several views:

Figure 1 is a side view of an electric connecting plug constructed in accordance with the invention.

Figure 2 is a longitudinal cross sectional view thereof.

Figure 3 is a forward end view of the improved plug.

Figure 4 is a transverse, cross sectional view of the plug on line 4—4, Figure 1.

Figures 5 and 6 are, respectively, longitudinal, cross sectional and forward end views of a modified form of insulating core, embodying the present invention.

Referring in detail to the drawing, 1 denotes a hollow, cylindrical body providing a chamber 2. The latter has an open rear end, and the forward end thereof is closed by a forward end wall 3 forming an integral part of the body.

A pair of parallel disposed, suitably spaced at-

taching prongs or contact arms 4, adapted for the inserted engagement in the conventional type of associated receiving element well known in the art, project forwardly from the body end wall 3, and have their rear end portions embedded and permanently fixed in said end wall. Each of the arms 4 carries a flat contact plate 5, which is of considerable area and disposed at right angles to respective arms at the inner side of the body end wall. The surface of the contact plates 5 are preferably disposed slightly rearward of the plane of the surface of the inner side of the end wall.

The chamber 2 is cylindrical, and a correspondingly-shaped insulating core 6 is removably mounted in the former. A pair of spaced flat contact plates 7 are embedded and permanently fixed in the forward end of the core. The surfaces of the contact plates 7 are disposed slightly forward of the plane of the forward face of the core, and have areas commensurate to the areas of the contact plates 5, with which latter they are adapted to make contacting engagement, when the core is assembled in the body 1. The core is formed with a longitudinally extending groove 8 for engaging a ridge 9 on the side wall of the chamber to prevent rotation of said core in the latter and thereby assure the accurate contacting engagement of the contact plates 7 with the contact plates 5.

The core 6 is maintained and secured in the body chamber 2, by a collar cap 10, which has a screw thread connecting engagement with the rear end of the body 1. The collar cap is formed with a central, inwardly disposed boss 11 engaging the rear end of the core, whereby the adjustment of the collar cap may be employed to forcibly maintain the contact plates 7 of the core in constant contacting engagement with the contact plates 5 of the body, as clearly illustrated in Figure 2. The peripheries of the body and collar cap are formed with knurled portions, respectively indicated at 12 and 13, for the obvious purpose of facilitating the adjustments of the cap on said body.

The end of a conductor cord 14, of any conventional construction, is permanently embedded and secured in the insulating core 6, and the terminals 15 thereof are splayed and permanently connected with respective contact plates 7, by means of welding, soldering, or in any other suitable manner, and are likewise permanently embedded in the core.

The connected end of the cord 14 extends through an aperture 16 provided therefor in the

collar cap 18, and through a suitable pull member 17, which latter has its forward end embedded and permanently secured in the rear end of the core 6, and likewise extends through the cap aperture 16. The pull member may be in the form of a spiral spring, as shown, or any other suitable, flexible pull device capable of serving as a pull element and of preventing the sharp flexing of the cord 14 at the connection of the latter with the plug structure.

It will be apparent that the improved plug structure, embodying conductors permanently anchored in the core 6 and virtually having conductors joined integral with the contact plates 7, as herein set forth, will provide a cord and plug set of relatively prolonged life and greater efficiency.

The modified form of insulating core 18, illustrated in Figures 5 and 6, differs from the core 6 in that the terminals 19 of the cord 20 are not permanently joined with the contact plates 21, but are detachably secured to the latter by screws 22 in the usual manner. The cord and terminals in this modified form are not permanently embedded in the core 18, and the latter is formed with suitable recesses 23 to allow the attachment of the cord to the core, or the detachment of the said cord from the latter.

The body 1, the cores 6, 18, and the collar cap 18, are molded to shape and may be constructed of any suitable, insulating composition material. Further, the contour of the body and cores may be varied to provide a configuration adaptable for use to best meet any conditions found in practice.

The present invention provides a most durable and efficient device of its kind, which may be economically constructed and employed in the manner and for the purpose set forth.

5 What I claim is:

An electric connecting plug for a conductor cord comprising the combination of a hollow cylindrical body having an open rear end and being provided with a wall closing the forward end thereof, a pair of forwardly projecting contact arms fixed in said wall and being provided with fixed contact elements disposed at the inner side of said wall, an insulating core mounted in said body and being provided with a longitudinally extending groove, and a pair of contact members fixed to the forward end of said core and contacting with respective contact elements, a longitudinally extending ridge formed on the inner periphery of said body and engaging in said groove for assuring the alignment of said contact members with said contact elements, the terminals of one end of said conductor cord being permanently embedded in said core and joined with respective contact members, an apertured cap having a screw thread connection with the open end of said body and including a boss engaging the rear end of said core for maintaining and securing the latter in said body and a spiral spring surrounding the connected end portion of the conductor cord and projecting through said apertured cap and having its forward end embedded and permanently secured in said core.

CHARLES H. KOHNE.
